COMBINATION TABLE LAMP AND SIGNAL LIGHT

Jerome D. Puzey, Clatskanie, and Frank T. Bloyd,
Rainier, Oreg.

Application March 28, 1955, Serial No. 35,241

Term of patent 14 years

(Cl. D48—20)

Fig. 1 is a perspective view of a combination table lamp and signal light showing our new design;

Fig. 2 is a side elevational view thereof to a smaller scale; and

Fig. 3 is a top plan view also to a smaller scale.

We claim:

The ornamental design for a combination table lamp and signal light, as shown.
